(57) **CLAIM**

The ornamental design for a canister with handle, as shown and described.

DESCRIPTION

FIG. 1 is a perspective view of a canister showing our new design;

FIG. 2 is a side elevational view of the canister with the opposite side being a mirror image thereof;

FIG. 3 is a rear elevational view thereof;

FIG. 4 is a front elevational view thereof;

FIG. 5 is a top view thereof; and,

FIG. 6 is a bottom view thereof.

The broken lines shown in the drawing disclosure are for illustrative purposes only and form no part of the claimed design.
